UNITED STATES PATENT OFFICE.

JACOB B. BLAW, OF PITTSBURG, PENNSYLVANIA, ASSIGNOR TO BLAW COLLAPSIBLE STEEL CENTERING COMPANY, OF PITTSBURG, PENNSYLVANIA, A CORPORATION OF NEW JERSEY.

CENTERING-MOLD.

No. 853,952.

Specification of Letters Patent.

Patented May 21, 1907.

Application filed November 2, 1906. Serial No. 343,005.

To all whom it may concern:

Be it known that I, JACOB B. BLAW, a citizen of the United States, residing at Pittsburg, in the county of Allegheny and State of Pennsylvania, have invented certain new and useful Improvements in Centering-Molds, of which the following is a specification.

My invention relates to collapsible centering molds for constructing concrete sewers, pipe, and the like; and has for its objects; to provide a collapsible mold of flexible material which may easily be collapsed and handled; to provide a mold having a superior bracing and collapsing means; and to provide a mold in which the bottom section can be placed separately, rendering the placing of the other sections more convenient, as hereinafter more fully explained. These and other objects are accomplished by my invention one embodiment of which is illustrated in the accompanying drawing in which,

The figure is a transverse section through a mold member.

My device is preferably constructed of thin sheet metal which can be easily handled and further can be detached from the concrete after it has set by a gradual or peeling action. Molds of this general type have heretofore been made in two sections as disclosed in my Patent Reissue #12,532 and this two section type is well adapted for small or medium sized sewers, but in larger sized sewers the sections become unwieldy and hard to handle and to meet this difficulty the type of device as illustrated in this application has been devised. In this type the mold member is divided into three or more parts instead of into two parts as in the old form, thus rendering the sections lighter and more easily handled, and furthermore in the particular form shown providing for the preliminary placing of the bottom section whereby the other side sections may be more easily placed than if all the sections were placed at the same time.

Referring to the drawing, 1, 2, and 3, are the mold sections of thin sheet metal, 1 being the bottom section, and 2 and 3 being the side sections, 4 and 5 are stiffening angles secured to the edges of the members 2 and 3 respectively, and overlapping the joints between the members 2 and 1, and 3 and 1,

6 are holding loops secured to the member 1 and extending through slots in the angles 4 and 5, through which loops holding wedges are adapted to be passed, 7 is a butt strap riveted to the member 2 and overlapping the joint between such member and the member 3, 8 is a holding loop secured to the member 3 and passing through the strap 7 and adapted to be held by a securing wedge in the same way that the loops 6 are held, 9 are stiffening angles extending longitudinally of the section 1 adjacent the upper edges thereof, 10 is a turnbuckle engaging holes in the angles 9, and 11, 12, and 13, are other turnbuckles extending transversely of the mold member and engaging the angles 4, 5, 14, 15, 16, and 17.

In operation, sufficient concrete is first placed to receive the member 1, which member is then placed in proper position and by means of the turnbuckle 10 is expanded to the proper extent. The members 2 and 3 can then be placed in position on top of the edges of the member 1 and secured together at the top, after which the turnbuckles 11, 12, and 13, are secured to the stiffening angles in the position shown and tightened to the proper extent. The concrete is then filled about the members 2 and 3 to the proper thickness and allowed to set, after which the mold may be collapsed. This is accomplished by first tightening the turnbuckles 11 and 13 until the lower edges of the members 2 and 3 are pulled inward, thus gradually loosening such members 2 and 3 from the concrete, after which the member 12 is tightened completely freeing the members 2 and 3 from the concrete, which members can be easily removed from the mold. The member 1 is loosened by tightening the turnbuckle 10 thereby drawing in the edges of the member and gradually loosening it from the engaging concrete, after which loosening the member can be removed and a new section of sewer started.

In cases in which the sewer formed is of very large diameter the number of side sections may, if desired, be made greater than two thereby reducing the weight of each section and rendering them more easy to handle. It will be apparent from the foregoing that the construction is advantageous for the reason that the member 1 can be preliminarily placed in position and the edges thereof will

act as guides for positioning the side members 2 and 3. Furthermore, after the member 1 is fixed in position, it serves as a path or support for the laborers while placing the side members. It will be seen that it is much easier to place a small section such as the section 1 accurately, and then position the other sections from it than it is to accurately position simultaneously two large sections as is the case when two semi-cylindrical members of the old type are used. The manner of bracing is also advantageous, the turnbuckle 10 constituting an effective means for simultaneously loosening the edges of the member 1, and the members 13 and 14 by virtue of their substantially radial positions giving the most effective bracing and affording a more direct and positive pull on the edges of the members 2 and 3 in collapsing than would be the case if the turnbuckles did not cross each other in the manner shown.

A further very important advantage of this construction arises where it becomes necessary to remove one section through one or more other sections, about which other sections the concrete is in process of setting. In such a case the section to be removed is separated into three component parts, and when the turnbuckles 10 are removed from the sections through which the knocked-down section is to be moved, room is provided between the member 1 and the braces 11-13 for the removal of the sections. This advantage, it will be seen, results from the three-part construction, together with the crossed brace construction which provides a large amount of space beneath the braces.

Having thus described my invention and illustrated its use, what I claim as new and desire to secure by Letters Patent, is the following:

1. In combination, a tubular mold member of flexible material comprising an independent parti-tubular bottom member, and a plurality of separable co-operating parti-tubular upper members, and means for collapsing the parti-tubular members. 45

2. In combination, a tubular mold member of flexible material comprising an independent parti-tubular bottom member and a plurality of separable co-operating parti-tubular upper members, and means for engaging the edges of the members whereby they may be sprung inwardly. 50

3. In combination, a tubular mold member of flexible material comprising an independent parti-tubular bottom member and a plurality of separable co-operating parti-tubular upper members, and turnbuckles for 60 bracing and collapsing the members.

4. In combination, a tubular mold member of flexible material comprising an independent parti-tubular bottom member and a pair of separable parti-tubular side members 65 engaging each other at their top edges and the lower member at their bottom edges, and means for collapsing the members.

5. In combination, a tubular mold member of flexible material comprising an independent parti-tubular bottom member having a turnbuckle engaging the opposite edges, and a pair of separable parti-tubular side members co-operating with the lower member and having a pair of crossed turnbuckles 75 for springing in the edges of the upper sections.

In testimony whereof, I hereunto sign my name in the presence of the two subscribed witnesses.

JACOB B. BLAW.
